(57) **CLAIM**

The ornamental design for a garment weight, as shown and
described.

DESCRIPTION

FIG. 1 is a perspective view of a garment weight showing our
new design;

FIG. 2 is a top plan view thereof;

FIG. 3 is a bottom plan view thereof;

FIG. 4 is a side elevation view thereof;

FIG. 5 is a perspective view showing the garment weight in a
separated configuration; and,

FIG. 6 is a perspective view of the garment weight showing
our new design in an in-use configuration.
